UNITED STATES PATENT OFFICE

2,677,881

CAN OPENER

Eric W. Anderson, Chicago, Ill., assignor to Dohm and Nelke Incorporated, St. Louis, Mo., a corporation of Missouri

Application August 17, 1949, Serial No. 110,791

6 Claims. (Cl. 30—5.5)

1

This invention relates to a can opener for conveniently opening a variety of sizes of filled cans.

Briefly, the invention consists in apparatus for commercial can-opening operations in quantity, and consists of a portable cabinet which is tiltable from an upright position on supporting legs, and casters, to a tilted position on the casters for movement, the whole unit being adapted conveniently to be grasped and tilted by a cutter-holding yoke. The cabinet contains pedal-operated mechanism for moving cans into cooperation with the cutter on the yoke which is selectively controlled from a conveniently operable hand lever to make its pedal-operated component effective for various types of cutters which are required for various sizes of cans accommodated. Other features will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a perspective view of the machine from its left front, showing the use of a cutter mechanism for smaller cans;

Fig. 2 is a view similar to Fig. 1, but showing the machine from the right front, showing the use of a cutter mechanism for larger cans;

Fig. 3 is a front elevation in orthographic projection, showing the machine with a cutter for large cans and parts in retracted positions;

Fig. 4 is a left-side view of Fig. 3;

Fig. 5 is a horizontal section taken on line 5—5 of Fig. 4, but showing the crusher parts in extended crushing position;

Fig. 6 is a cross section taken on line 6—6 of Fig. 3, but showing parts in position for operation upon small cans;

Fig. 7 is a detail section taken on line 7—7 of Fig. 6;

Fig. 8 is a detail longitudinal section of a cutter head for smaller cans;

Fig. 9 is a plan view of Fig. 8; and,

Fig. 10 is a detail section taken on line 10—10 of Fig. 9.

Similar reference characters indicate corresponding parts throughout the several views of the drawings.

Referring now more particularly to Figs. 1 and

2, there is shown at numeral 1 a cabinet which is supported at the rear on casters 3 and at the front on legs 5. When upright, the legs 5 prevent the device from creeping, but it may be tilted backward on casters 3 for trundling movement to any desired position. To the top of the cabinet is bolted a yoke 7 which has other primary functions but is also used as a handle for conveniently effecting the stated tilt and movement. In the left-hand portions of the cabinet 1 is certain mechanism described below for reciprocating a can-support or table 9, this mechanism being under control of a left-foot pedal 11. This mechanism is also adjustable from a manual operating lever 13 on the left side of the cabinet. This adjusts the mechanism operated by pedal 11 to force small cans into association with one type of cutter head shown in general at numeral 15 (Fig. 1), or for adjusting the mechanism to force large cans into association with another type of cutter head shown in general at numeral 17 (Fig. 2).

On the right side of the cabinet 1 is a receptacle 19 having a top opening 21 conveniently located with respect to the table 9 for the reception of opened and emptied cans. With the stated mechanism in cabinet 1 is a crusher mechanism which is operated from a second and right-foot pedal 23. Cans which are dropped into the receptacle 19 through opening 21 are retained therein until flattened by the crushing mechanism, which is operative from pedal 23. The receptacle 19 has a lower restricted opening at 29 which does not show in Figs. 1 and 2, but does appear in certain of the other figures to be described. This opening is so positioned and is of such limited width and elongate shape that it will release only flattened cans which drop into a waste pile such as suggested at 27.

It should be noted before giving further detailed description, that the parts of the apparatus are arranged for convenient operation by an operator standing in front of it. He may employ one or the other for operation of the pedals 11 and 23, his left hand for operating the lever 13, and both hands for applying and removing cans to and from the table 9 and for dropping cans into the receptacle 19. Crushed cans need not be handled until removed from the pile 27. The pedals 11 and 23 extend from an opening 29 in such a way that the reactions required for operating them are substantially applied to the legs 5, so that the machine does not creep during operation. On the other hand, the machine may be easily moved by grasping the yoke

1 and tilting it backward, whereupon it may be trundled on the casters 3 to any desired new location.

Referring now more particularly to Figs. 3-6, it will be seen that the can table 9 is carried upon a stem 31 which is vertically movable in a bearing 33 extending down from the top 35 of the cabinet. The lower end of the stem 31 is hollow for the rocking reception of a push rod 37, the latter being pivoted at 39 to a rocker 41. At its other end, the rocker is pivoted at 43 to the clevis of a connecting rod 45, the latter being pivoted at 47 to an operating pedal arm 49 which carries the pedal 11. The pedal arm is pivoted at 51 to a bracket 53 attached to a bottom piece 55 attached to the cabinet 1. A spring 57, which is anchored at 59 and attached to the pedal arm 49 at 47, serves to bias the pedal arm 49 upward to let down the table 9.

The rocker 41 is unusual in that it does not rock on a fixed pivot. The rocking arrangement is shown best in Figs. 4, 6 and 7. It consists in a fixed bracket 61 which is braced by a rod 63. This bracket carries an arcuate slot 65 for accommodating the movement of a cross pin 67, on which is a pivot roller 69. The pin 67 is carried upon coordinate arms 71, keyed to a rock shaft 73, the latter being carried in bearings 75 of the bracket 61. Rock shaft 73 passes to the outside of the cabinet 1, where it is provided with the lever 13 keyed thereto. These parts 71, 73 and 13 constitute a lever assembly. Thus when the lever 13 is oscillated, the coordinate levers 71 oscillate, to move the pin 67 in the slot 65. Therefore, the pivot roller 69 may assume selected positions at opposite ends of the slot 65 which may be compared in Figs. 4 and 6.

Selective positioning of the pivot roller 69 controls the manner in which the rocker arm 41 will operate in response to depression of the pedal arm 49. This is accomplished by arranging a slot 77 in the rocker 41 within which the pivot roller 69 fits. Bracket 61 has two side cheeks 79 sandwiching the rocker arm 41 thus determining its plane of motion. The pivot roller 69 in its position in slot 77 is also sandwiched between the cheeks 79 and is held captive, the slots 65 being narrower than the roller diameter. When the pivot roller 69 takes up a rearward position (handle 13 back) such as shown in Fig. 4, it also takes up a rearward position in the slot 77. When the pivot roller 69 takes up a forward position in the slot 65 (handle 13 forward), it also takes up a position at the front end of the slot 77. In the former position (Fig. 4), rocker 41 when oscillated by depression of the pedal arm 49 will provide a high lift for the pivot 39 and hence for the table 9. In the latter position (Fig. 6), the same rocker 41 when oscillated by depression of the pedal arm 49 will provide a low lift for the pivot 39 and hence for the table 9. In proceeding between its extreme positions the pivot means 67, 69 may move rapidly. It is held in either of its extreme positions by the overcentering detent means constituted by the slots 65 and 67. The end of rocker 41 at pin 43 is detained against lateral shift when in upward position. This is effected by detent recesses 42 in the cheeks 79, which recesses act as holding sockets for the upper clevis-end of link 45. This detent means of the slot 77 is concave upward, thereby causing its ends to act also as detents so that once the lever 13 is thrown either backward or forward

ward it will so remain, with the result that the desired pivot position of roller 69 will be retained. Hence the linkage 49, 45, 41, 37, controlling table 9, will after setting retain either of its two positions for high lift of table 9 (Fig. 4) or lower lift of that table (Fig. 6). For the high-lift operation, the table starts from a lower elevation (Figs. 3 and 4) than the starting elevation for the low-lift operation (Fig. 6). This in effect increases the can-receiving throat of the machine between overhang 85 and the table, which is for accommodating larger cans.

The purpose of the variable-lift operation of the table 9 is to lift a small can a short distance when the lever 13 is forward (Fig. 1) or a large can a greater distance when the lever 13 is rearward (Fig. 2). As stated, the lowering of the starting position of table 9 for large-stroke operation provides for acceptance of longer cans. The greater stroke of movement for larger cans is desired by reason of the fact that a cutter is required for these which requires a longer actuating stroke than is the case for smaller cans. The cutter assemblies 15 (small can) and 11 (large can) are interchangeable, as illustrated in Figs. 1 and 2. Each assembly includes a supporting rod 81 or 82 adapted to be fastened in an opening 83 in the overhang 85 of the yoke 7. The rods may be interchangeably fastened by a hand screw 87.

The cutter assembly 15 for small cans will first be described, this being shown in detail in Figs. 8-10. It consists of a head 89 recessed as shown at 91. On the one side of the recess is a semi-circular positioning and guide shoe 93. In the recess 91 is a flexible band type saw blade 95 which is held in position from the inside by a split spring ring 97. A screw-operated wedge 99 under control of an adjusting nut 101 cooperates with the split 103 in the ring 97. When the nut 101 is turned so as to draw up the wedge 99, the ring 97 is expanded radially to wedge the cutter blade 95 against the sides of the recess 91. Passing through an opening 105 in the head 89 is a spring-retracted hand punch 107, by means of which any heads removed from the cans by the cutter blade 95 may be punched out of the latter. As will appear, cutting action occurs when a can properly positioned on the table 9 by guide 93 is lifted by rising action of the table, to have its head pushed into the cutter 95. It will be seen that the cutter blade 95, for small cans, has several relatively shallow teeth, which require for complete lid removal only a short-stroke action 55 for the can lift, which corresponds to the arrangement of the parts shown in Figs. 1 and 6.

The form of opener for large cans is shown in Figs. 2, 3 and 4, wherein the shorter supporting rod 82 is provided with a head 109, the rim of which is recessed as shown at 111 to accept two semicircular spade-type cutters 113, the cutting edges of which are deep and angular, as indicated in Fig. 4. A split holding ring is shown at 115 adapted to be expanded by the expansion bolt 117. This bolt is of the same general type as that described in connection with Fig. 10, and consequently requires no further explanation beyond the showing in the drawings. After inserting the cutters 113 into the recess 111 and the expansion ring 115, the cutters are held in place by drawing up the expansion bolt 117 so as to expand the split ring 115, thus anchoring the cutters.

A semicircular positioning and guide shoe 119 also depends from the head 109. No knockout

means is shown in connection with this form of cover, but it will be understood that one may be used. With the cutter described, knockout may be effected by introducing a member through the head 109, which is spoked to permit this. This spade type of cutter requires a greater movement of the can for effecting a complete cut; wherefore the provision of the adjustment of the lifting mechanism in the position shown in Figs. 3 and 4, wherein the pivot roller 69 is back in the groove 65, thus providing a greater stroke of lifting action for the table 9.

After one end of a can is removed, it will be emptied. It may then be inverted and the other end removed, after which the can is dropped into the receptacle 19. This receptacle is constituted by spaced walls 121, 123, a ribbed end wall 125 and a bottom 127, the latter extending to an open slot or narrow discharge opening 129. Movable to and from the opening 129 is a ram 131 carried on rollers 133. This ram is supported also by guiding pins 135 which slide in fixed cylindric guides 137, the latter being rigidly supported in bosses 139 attached to the framework of the cabinet 1. The ram 131 is operated by a toggle linkage consisting of a link 141 pivoted to the ram by means of pin 143, and a second link 145 pivoted to a bracket 147 on the cabinet 1 by the pivot pin 149. These two links are pivoted by a pin 151 at a knee joint. Depending from the pin 151 is a pull link 153 to which, at 155, is pinned a pull rod 157. The latter at its lower end is pinned as at 159 to a second pedal arm 161 which carries a pedal 23, the latter being also pivoted on the pin 51 already described. This arm is biased upward by a spring 163. When the pedal 23 and arm 161 are depressed, the pull rod 157 and link 155 pull down the pin 151 so as to straighten the toggle 141, 145, thus driving the ram 131 through the receptacle 19 to crush against the ribbed end wall 125 any empty container therein. The container will be crushed into a flat plane over the opening 129 so that when (by releasing the pedal 23) the spring 163 causes retraction of the ram, gravity will force the flattened can through the narrow opening 129 to the pile 127.

Complete operation is as follows:

By grasping the yoke 7 and tilting the cabinet 1 backward on wheels 3, it may be trundled into any desired position and then permitted to gravitate back into upright position. Assuming that small cans are to be opened, the cutter assembly 15 is locked into position on the yoke 7 by means of the hand screw 87. This cutter assembly, having the shallow-tooth blade 95, calls for setting the lever 13 in its forward position, which provides a forward pivot point for the rocker 41 and a short lift stroke for the table 9. This also places the table 9 in its upper initial position so as to minimize the amount of extension required in the rod 81 for supporting the cutter at the proper distance above the table 9.

Next a can is placed on the table in contact with the positioning shoe 83 and pedal 11 is depressed. This elevates the table 9 to force the can into the cutter, which removes the top. Thereafter the pedal 11 is released, whereupon the can descends. The can may then be removed and emptied and the top knocked out of the cutter assembly 15. The can may then, if desired, be inverted and have its bottom cut out. Upon this removal, the can is dropped into the opening 21 and into the compartment 19. The pedal 23 is depressed, with the result already described, the flattened can finally dropping through the opening 129.

To operate upon large cans, the lever 13 is placed in its rearward position (Fig. 4). This depresses the table 9 to a new and lower starting position and pivots the rocker 41 for greater table lift. The cutter assembly 17 is then applied and operation proceeds as before, except that knockout of the can lids is accomplished by pushing with any handy rod between the spokes of the head 109.

If the contents of a can spill during any opening operation, they are caught in a depression 171 formed in the top 35 and drained out rearwardly over a lip 173.

The apparatus has certain advantages by reason of its arrangements of parts. The arrangement of the yoke for supporting the assembly 15 or 17, and its relationship to the casters 3 so that it may be used as an arm to trundle the apparatus about when it is tilted on the casters 3. Operation of the lever 13 is conveniently performed by the left hand when an operator is standing in front of the machine in order to tread on the pedals 11 and 23 with his left and right feet, respectively. His right hand can conveniently drop the containers into the compartment 19. Both hands may be used to position the container on the table 9. Because of the non-wheeled legs 5 and the position of the pedals 11 and 23, operative reactions on the floor serve to hold the apparatus in position.

The means for changing the throw of pivot point 39 on rocker 41 is a mechanically convenient one for adapting the table lift to various sizes of cans. Moreover, it is of such a nature that for the larger sizes of cans the table 9 is dropped into a position to accommodate cans of maximum length for a given throat distance provided by the yoke 7 with its attached assembly 17. Various cutter assemblies may be conveniently stocked for simple application to the yoke by means of the hand-wheel 87. The toggle links 141 and 145 buckle upwardly in retracting the ram, and straddle both their own operating linkages and the elevating rocker linkage for the table 9, both of the latter linkages extending downward in the cabinet 1. This makes a compact arrangement wherein only the receptacle 19 forms an extension; and this extension is advantageous in positioning the outlet 129 for a convenient dropout of the meshed cans to one side of the cabinet, where a pile of such cans will not interfere with the actions of the operator standing in front of the machine.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. In a can opening device of the type comprising a support, a downwardly directed cutter fixed to the support, and table for holding a can carried by the support for vertical movement below and in line with the cutter, said table being adapted for upward movement toward the cutter for cutting the top of a can on the table, and for downward retractive movement away from the cutter; means for determining high and low initial positions of the table and for moving the table from either of said positions toward the cutter comprising a bracket fixed to the support

having a slot formed to have its ends offset in one direction, a pin shiftable in the slot between a first position at one end of the slot and a second position at the other end of the slot, means carried by the support for shifting the pin between its said positions, a rocker having a slot formed to have its ends offset in the opposite direction with respect to the ends of the slot in the bracket and mounted on said pin for rocking movement on the axis of the pin, the pin being shiftable on the axis of the pin, the pin being shiftable from one end of the slot in the rocker to the other, means coupling one end of the rocker and the table, and a foot pedal and means coupling the foot pedal to the other end of the rocker for moving the table toward the cutter, the pedal having a raised retracted position wherein the table occupies either its high or low initial positions depending upon whether the pin is at one end or the other of the slots.

2. In a can opening device as set forth in claim 1, detent means operative between the rocker and the support for preventing the rocker from moving endwise when the pedal is in its retracted position.

3. A can opening device as set forth in claim 1 wherein the bracket has a recess receiving the coupling means between the foot pedal and the rocker when the pedal is in its retracted position for preventing the rocker from moving endwise.

4. A can opening device as set forth in claim 1 wherein the slots are formed with the offset ends by being made arcuate, with the slot in the bracket and the slot in the rocker reversely curved.

5. A can opening device comprising a cabinet, a cutter yoke extending upward from the top of the cabinet and carrying a downwardly directed cutter spaced from the top of the cabinet, a stem extending through an opening in the top of the cabinet and adapted for vertical movement in alignment with the cutter, a can table on the upper end of the stem, a bracket mounted inside the cabinet, a horizontal rock shaft journaled in said bracket extending out of the cabinet through an opening in the cabinet, an operating lever on the outer end of the rock shaft, the bracket having an arcuate slot centered generally in the axis of the shaft and concave downward, a radial

arm fixed on the rock shaft carrying a horizontal pin extending through said arcuate slot, the pin being shiftable from one end of the slot to the other by rocking the shaft by means of the lever, a rocker having an upwardly concave arcuate slot receiving the pin and being adapted for rocking movement on the axis of the pin, the pin being shiftable from one end of the slot in the rocker to the other, a foot pedal pivoted at one end inside the cabinet and extending out of the cabinet at its other end through an opening in the cabinet, a coupling between one end of the rocker and the stem, a coupling between the foot pedal and the other end of the rocker for lifting the stem and table when the pedal is pushed down, and spring means biasing the pedal upward to a raised retracted position wherein the table occupies either a high or low initial position depending upon whether the pin is at one end or the other of the slots.

20 6. A can opening device as set forth in claim 5 wherein the bracket has a recess receiving the end of the coupling between the foot pedal and the rocker where it is connected to the rocker when the pedal is in its retracted position for preventing the rocker from moving endwise on the pin.
